UNITED STATES PATENT OFFICE.

DAVID W. BOWE, OF DETROIT, MICHIGAN.

MOLD FOR CONCRETE STRINGERS.

Application filed July 7, 1923. Serial No. 650,076.

To all whom it may concern:

Be it known that I, DAVID W. BOWE, a citizen of the United States, residing at Detroit, in the county of Wayne and State of Michigan, have invented a new and useful Mold for Concrete Stringers, of which the following is a specification.

This invention aims to provide a simple means whereby a concrete railway stringer or like structure may be fashioned and reinforced.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 is a plan; Figure 2 is a section on the line 2—2 of Figure 1; Figure 3 is a section on the line 3—3 of Figure 1; Figure 4 is a section showing a modification; Figure 5 is an elevation showing one of the clamps; Figure 6 is a section taken through the clamp; Figure 7 is a cross section showing a modification.

Referring to Figures 1, 2 and 3, the device is shown as comprising a base including outer longitudinal members 4 and an inner longitudinal member 4^a therebetween, the outer longitudinal members being secured to transverse stringers 1 and the inner longitudinal member being free, to serve as a pallet on which the finished product may be removed. The members 4 and 4^a have transverse end cleats 2. Adjacent to their edges, the members 4 and certain of the stringers 1 carry suspension devices 3 whereby the entire mold, either filled or empty, may be handled conveniently. Outer longitudinal cleats 70 are secured to the members 4, and inner cleats 5 are secured thereto. A multi-part filler 6 is secured to the members 4 and 4^a and is adapted to form a concavity in the bottom of the finished product.

The mold comprises in addition to the base, a body including sides 7 resting on the members 4, between the cleats 5 and 70. Fixed outer top sections 8 are secured at 9 to the sides 7. The body of the mold includes ends 10 seated on the members 4 and 4^a inwardly of the cleats 2. The fixed outer top sections 8 are secured at 11 to the ends 10. Inner fixed top sections 12 are spaced from the top sections 8 and are secured at 14 to the ends 10. Movable top sections 15 are disposed between the top sections 8 and the top sections 12. The movable top sections 15 are connected by hinges 16 to the outer top sections 8 and rest upon the ends 10. Openings 17 are formed in the top sections 12 and 15 at the meeting edges thereof. The openings 17 preferably are formed in one top portion of the body of the mold, only, as indicated in Figures 2 and 1. Eyes 71 are fixed to the inner longitudinal member 4^a of the base and are adapted to be engaged by hooks 72 pivoted on the ends 10, to hold the body of the mold on the base of the mold. When the body of the mold is removed from the finished product, the eyes 71 may be used to lift the inner longitudinal member 4^a, and with it, the finished product which is formed in the mold. Eyes 73 are secured to the fixed outer sections 8 of the mold top and may be used to lift the body of the mold off the base and off the finished product.

The numeral 18 marks a rectangular frame including end bridges 19. The end bridges 19 rest on the end members 10 of the mold and are held thereon by dowel pins 21. The end bridges 19 of the frame 18 are connected by longitudinal bars 20, which may be angle members. Intermediate transverse bridges 22 are connected to the longitudinal bars 20. Each bridge 22 comprises a bottom member 23 and a top member or arch 25. The parts 23 and 25 of each bridge are connected by securing elements 29, as are the constituent parts of the end bridges 19. The bottom members 23 of the bridges 22 have outwardly extended feet 24 overlapped on the top members 12 of the body of the mold. The feet 24 have slots 27, receiving securing elements 28 (bolts) carried by the top members 12 of the body of the mold. The longitudinal bars 20 are connected by securing elements 26 to

the top members of the bridges 22 and 19. Longitudinal bars 30, which may be angle members, are held by the securing elements 29 on the bridges 19 and 22 and are disposed in close relation to the inner edges of the top members 12 of the mold.

Longitudinal reinforcing rods 31 are located within the mold. The rods 31 pass through crossed transverse bars 32. The lower ends of the bars 32 are engaged with the sides 7 and rest on the cleats 5. The upper ends of the crossed transverse bars 32 abut against the longitudinal bars 30 of the frame 18. One of the longitudinal reinforcing rods 31 passes through the bars 32 at their place of crossing. That rod and the cross bars 32 are held together releasably but securely by separable clamps 33. The ends of horizontal ties 34 are connected to the lowermost reinforcing rods 31. Securing elements 35, such as hook bolts, are engaged at their lower ends with the ties 34. The securing elements 35 pass upwardly through the bridges 22 and through the bars 20 of the frame 18. Brackets 36 are mounted at their inner ends on the reinforcing rods 31 which connect the cross bars 32 at their place of crossing.

Each bracket 36 is sustained by a brace 37 extended downwardly to one of the bars 32. The openings 17 in the top of the mold are adapted for the reception of brackets 36 and the braces 37.

In practical operation, the movable top sections 15 are opened and the mold is filled with concrete, as shown at 38. The nuts on the upper ends of the securing elements or hook bolts 35 are removed, and the bolts 28 are released from the feet 24 of the bridges 22. Thereupon the frame 18 may be removed. The ends 10, the sides 7, and the parts 8, 12 and 15 of the mold may be removed, either together or separately. The product, supported by the member 4^a may be lifted out of the mold, through the instrumentality of the eyes 71 on the ends of the member 4^a. The rods 31, the bars 32, the ties 34 and the securing elements or hook bolts 35 remain in the product, the upper ends of the hook bolts being exposed, to serve as an attaching means for rail chair or the like. The brackets 36 project laterally from the finished product and constitute a means whereby one stringer, through the instrumentality of any suitable connecting means (not shown), may be united to another stringer.

In Figure 4, the base 39 is of the form hereinbefore described, the stringers appearing at 40. The base 39 has a marginal rib 41 carrying suspension devices 42. The body of the mold comprises ends 43 and sides 44 held in place by the rib 41. The top sections 45 have suspension devices 100 and are secured to the sides 44. The frame, corre-

sponding to the frame 18 is of the kind hereinbefore described, and is denoted by the numeral 46. The hook bolts are shown at 47, the ties at 48, the crossed bars at 49 and the bracket at 51. One of the top members 45 has a recess 53 receiving the outer end of the bracket 51. The bracket does not project entirely through the top member, as does the corresponding bracket 36 in Figure 2. It will be understood that the form shown in Figure 4 includes the bridge 19, hereinbefore described.

The operation of the device delineated in Figure 4 does not differ materially from the operation of the form shown in Figure 2, aside from the fact that the form shown in Figure 4 does not have the movable top sections 15 of Figure 2.

In Figure 7, the base 54 of the mold is constructed as hereinbefore described and is supported on stringers 55. The base has a marginal rib 56 provided with suspension devices 57. The ends of the body of the mold are shown at 58, and the sides at 59, these parts being received within the ribs 56 and being supported on the plate 54. There are suspension devices 101 on the sides 59. The frame is denoted by the numeral 61 and its bridges cooperating with the hook bolts 62. The ties are shown at 63, the longitudinal reinforcing rods at 64, the crossed bars at 65, the bracket at 66 and the brace at 67. One of the side members 59 is provided with a recess 68 for the reception of the bracket 66. It will be understood that the form shown in Figure 7 is provided with the end bridges 19 hereinbefore described.

Generally stated, the device is so constructed that the concrete stringers may be formed advantageously either in the shop or on the right-of-way. The mold may be taken down readily after the concrete stringer has set, and the stringer, when completed, will be adequately reinforced.

What is claimed is:

1. In a device of the class described, a mold including a base; a body comprising sides and ends supported on the base; a frame extended between the ends and located between the sides; means for securing the frame releasably to the sides; pairs of crossed members engaged at their lower ends with the sides and cooperating at their upper ends with the frame, to brace the mold; ties connecting the crossed members of the pairs adjacent to their lower ends; and securing devices forming a releasable connection between the ties and the frame.

2. In a device of the class described, a mold comprising a base; a body comprising sides and ends supported on the base; fixed inner and outer top sections carried by the ends, the outer top sections coacting with the sides; hinged top sections closing the space between the inner and outer top sec-

tions; a frame releasably connected with the inner top sections; crossed braces extended between the sides and the frame to support the mold; ties connecting the crossed members at their lower ends; securing elements connecting the ties with the frame; and a bracket projecting from the crossed mem-

bers, one of the top sections having an opening for the reception of the bracket. In testimony that I claim the foregoing as my own, I have hereto affixed my signature.

DAVID W. BOWE.
